DISPLAY RACK DIVIDER

Daniel M. Ganz, Baldwin, N. Y., assignor of one-half to
Harold Mahler, New York, N. Y.

Application April 1, 1955, Serial No. 498,731

5 Claims. (Cl. 211—184)

The present invention relates broadly to display racks and fixtures, and in particular to an improved removable and adjustable divider for use with such display racks or fixtures.

Known display racks for the merchandising and sale of stationery items such as greeting cards, usually include a plurality of tiers arranged in step-wise relation, each of the tiers including spaced front and rear walls defining a trough which is adapted to receive plural stacks of cards or the like in side-by-side relation. In that the stacks of cards or similar articles which are displayed in the racks vary in width, and are frequently changed or displayed at different locations in the rack, it is impractical to attempt to separate the regions for the respective stacks by rigid partitions or dividers.

Broadly, it is an object of the present invention to provide a removable and adjustable divider for use on a display rack which is adapted to accommodate plural stacks of cards or the like in side-by-side relation.

It has been suggested that the trough or channel of the display rack may be separated into individual pockets or bins by the use of spring-wire clips which are hooked over one of the walls and extend into the space between the respective walls. Such spring clips may be moved longitudinally of the wall and adjusted to fit cards or articles of various sizes when displayed upon the rack. However, such spring clips are usually dimensioned for association with a display fixture or rack of a particular size, specifically one with a predetermined separation between the walls defining the width of the trough or channel. Still further, such known spring-wire clip dividers are somewhat ineffective to preclude interleaving of articles from adjacent stacks or packs, especially when the display rack is rather full.

Accordingly, it is a further object of the present invention to provide improved dividers which may be accommodated on display racks having troughs or bins of varying widths and are effective to completely subdivide or partition the troughs into individual compartments or pockets. To advantage, dividers according to the present invention may be adjusted longitudinally and transversely of the walls defining the trough for the subdivision of the trough into pockets each substantially of the width of the associated stack of cards.

In accordance with an illustrative embodiment demonstrating features of the present invention, there is provided a divider for use on a display rack which includes a downwardly opening clip engageable over one of the trough-forming walls of the display rack, a divider body extending in a plane substantially at right angles to the clip and to the trough-defining walls, and means operatively connected to the divider body for adjustment transversely of the trough. The divider body is movable into a position straddling the space between the walls, thus being effective to define a complete partition across the trough. To advantage, the assembly of the clip and the divider body is adjustable along the length of the wall such as to fit cards or articles of various widths.

2
The above brief description as well as further objects, features and advantages of the present invention will be best understood by reference to the following detailed description of several illustrative embodiments, when taken in conjunction with the accompanying drawing, wherein:

Fig. 1 is a fragmentary perspective view showing a somewhat conventional display rack or fixture having a divider embodying features of the present invention mounted thereon;

Fig. 2 is an elevational view on an enlarged scale taken substantially along the line 2—2 of Fig. 1 and showing details of the divider;

Fig. 3 is a perspective view of the divider illustrated in Figs. 1 and 2;

Fig. 4 is a sectional view taken substantially along the line 4—4 of Fig. 3; and

Fig. 5 is a perspective view of a modified divider embodying further features of the present invention.

Referring now specifically to the drawings, there is shown in Fig. 1 a display rack or fixture 10 including a base 12 of step-like configuration and upright walls 14, 16 which extend parallel to each other. In the portion of the display rack illustrated, the uprights 14, 16 serve as front and rear walls respectively for a trough or channel 18 which extends across the width of the display rack and includes a floor or bottom 20 defined by one of the steps of the base 12.

In accordance with the present invention, a divider, generally designated by the reference numeral 30, is mounted on the front wall 14 of the trough or channel 18 to separate adjacent stacks S₁, S₂ of greetings cards or similar articles from each other. The divider includes a downwardly opening clip 32 of generally U-shaped configuration having leg sections 34, 36 interconnected by a curved bight 38. The leg section 34 is somewhat longer than the leg section 36, but both have substantial area contacts with the opposing faces of the wall 14 to preclude tipping or tilting of the clip when mounted on the wall. The leg section 34 is formed with inwardly projecting dimples 40 integral with the wall for grippingly engaging the inner face of the wall 14 to further preclude tipping. The outer wall 36 of the clip 32 is formed with an outward lip 42 such that the user may place an instrument beneath the lip to disengage the same in the event it is difficult to manually remove the clip from the wall. The clip is fabricated of resilient or springy material such that the area contact provided by the inner surfaces of the opposed leg sections 34, 36 assure gripping contact of the opposite faces of the wall 14.

Integral with the lower end of the leg section 34 are ears 44, 46 which are preferably struck out from the leg section 34. The ears 44, 46 in conjunction with a pin 48 serve to provide a pivotal mount for a transparent plastic divider body 50 which extends generally in a plane at right angles to the clip and to the respective walls 14, 16 of the trough 18. The pin 48 which in actual manufacture may be a rivet, urges the inner surfaces 44a, 46a of the ears into frictional contact with the coextensive surfaces of the divider body 50, such that the divider body will maintain various positions of adjustment when positively urged into such positions.

The divider body 50 is formed with a cutout 52 defining an integral nose or projection 54. The cutout is dimensioned in relation to the clip 32 such that the edge 52a may abut against the leg section 34 in an inner or retracted limit position; the length of the nose 54 is such that the nose projects over the clip 32 in various positions of adjustment from the inner limit or retracted position wherein the edge 52a is substantially upright and abuts against the leg section 34 to the outer limit posi-

tion illustrated in Fig. 2 wherein the divider body 50 has an edge in contact with the rear wall 16 of the trough. Thus in various positions of adjustment, the nose 54 provides an extension of the divider body 50 which assures complete bridging of the space between the walls 14, 16.

In actual use, the clip 32 is engaged over the wall 14 and adjusted to the desired position, whereupon the divider body 50 is pivoted until it assumes the position straddling the trough and in contact with the rear wall 16, as illustrated in Fig. 2.

In Fig. 5, there is shown a modification of the present invention in which the divider body 50' is loosely mounted between the ears 44', 46' of the clip 32' and into an outer limit position defined by the proximity of the rear wall 16 to the front wall 14. The spring 60 includes a medial portion bent about the pivot pin 48', a terminal section 62 bearing against the leg section 34' of the clip 32' and a hook terminal section 64 engaged about the divider body 50'.

Still further modifications will occur to those skilled in the art, and accordingly the appended claims should be construed broadly and in a manner consistent with the disclosure herein; in certain instances some features of the invention will be used without a corresponding use of other features.

What I claim is:

1. In combination with a display rack including front and rear walls spaced apart and in substantial parallelism, said walls defining an elongated trough for receiving side by side stacks each made up of a number of flat elements, an upright divider for said display rack including a downwardly opening metal clip of U-shaped cross-section, said clip having opposed legs engaging over one of said walls, a divider body extending in a plane transverse to said walls, and a pivot on one leg of said clip and operatively connected to said divider body mounting same for adjustment in said plane and into a position straddling said walls and serving as a barrier against interleaving of the elements of the respective stacks.

2. In combination with a display rack including front and rear walls spaced apart and in substantial parallelism, said walls defining an elongated trough for receiving stacks made up of a number of flat elements in adjacent and side by side relation, an upright divider for said display rack including a downwardly opening metal clip of U-shaped cross-section, said clip having opposed legs engaging over one of said walls, a divider body extending in a plane transverse to said walls, pivot means on one leg of said clip and operatively connected to said divider body mounting same for adjustment in said plane and into an operative position straddling said walls and serving as a barrier against interleaving of the elements of the respective stacks, and a spring operatively connected to and biasing said divider body into said operative position.

3. In combination with a display rack including front and rear walls, spaced apart and in substantial parallelism, said walls defining an elongated trough for receiving

stacks made up of a number of flat elements in adjacent and side by side relation, an upright divider for said display rack including a downwardly opening metal clip of U-shaped cross-section, said clip having opposed legs engaging over one of said walls, inwardly projecting dimples integral with one of said legs for grippingly engaging said one wall, a divider body extending in a plane transverse to said walls, and a pivot on one leg of said clip and operatively connected to said divider body mounting same for adjustment in said plane into a position straddling said walls and serving as a barrier against interleaving of the elements of the respective stacks.

4. In combination with a display rack including front and rear walls spaced apart and in substantial parallelism, said walls defining an elongated trough for receiving stacks made up of a number of flat elements in adjacent and side by side relation, an upright divider for said display rack including a downwardly opening metal clip of U-shaped cross-section, said clip having opposed legs engaging over one of said walls, a divider body extending in a plane transverse to said walls, and means on one leg of said clip and operatively connected to said divider body mounting same for adjustment in said plane from a retracted position into an operative position straddling said walls and serving as a barrier against interleaving of the elements of the respective stacks, said divider body including an integral nose projecting over said clip in various positions of adjustment of said divider body.

5. In combination with a display rack including front and rear walls which are spaced apart and extend in substantial parallelism, said walls defining an elongated trough for receiving stacks made up of a number of flat elements in adjacent and side by side relation, an upright divider for said display rack including a downwardly opening metal clip of substantially U-shaped cross-section, said clip having opposed legs engaging over said front wall, a divider body extending in a plane transverse to said walls, a pivot on one leg of said clip and operatively connected to said divider body mounting same for pivotal adjustment in said plane into a position straddling said walls and abutting said rear wall, said divider body serving as a barrier against interleaving of the elements of the respective stacks, and means on said clip and engaging said divider body providing frictional contact therebetween whereby said divider body will maintain a prescribed position of adjustment when positively urged into said prescribed position.
